11 Claims. (Cl. 122—336)

This invention relates to a steam generator in which the gases flow in a horizontal combustion chamber in the longitudinal direction and in which, laterally adjacent to the combustion chamber, flues are arranged for combustion gases flowing parallel to the gas current in the combustion chamber.

There exist steam generators with combustion chambers in which the flames are conducted horizontally in the longitudinal direction and in which the gases at the rear end of the combustion chamber enter into gas flues located laterally adjacent to the latter. In these gas flues the gases are also conducted horizontally and parallel to the longitudinal direction of the combustion chamber. Steam generators of the mentioned type are advantageous on account of their relatively low height. However, with the conventional steam generators great difficulties are encountered when it is necessary to clean or exchange the tubes of the convection heating surface which are not readily accessible.

The present invention aims to provide an improvement in the arrangement and formation of the heating surfaces of steam generators with horizontally conducted flames in the combustion chamber and horizontally conducted gases in the gas flues which are located parallel to the longitudinal extension of the combustion chamber and in which the gases are conducted also parallel thereto.

Another object of the invention consists in the provision of a steam generating heating surface in the horizontal gas flues which heating surface is made up of individual groups of parallel banks of tubes, which are connected to lower distributors and upper collectors arranged transversely with respect to the direction of the gas flow. The invention further aims to render the space above the collector of the mentioned groups of tubes readily accessible and especially free from other tubular structures.

The invention further aims to arrange the steam separator drum above the combustion space wherein preferably the gas flues adjacent the combustion chamber are arranged on the one side thereof whereas the steam separator drum is also located in the longitudinal direction of the combustion chamber but on the opposite side. This structure offers the advantage that the combustion chamber and the heating surfaces in the gas flues may be relatively high within the above mentioned relatively low height of the steam generator.

The invention further aims to form the convection heating surfaces of groups of tubes which are all of a substantially equal structure so that the numbers of such groups need only be enlarged or reduced for boilers of varying outputs. Thereby even boilers with a super-heater arranged within the convection heating surface require only a minimum number of different types of tubular elements.

Another object of the invention is to form the mentioned groups of straight, vertical tubes or of tubes which are substantially straight in a projection at right angles to the cross-section of the gas flues. Such structure results not only in favorable conditions for the heat transfer, but also the tightening of the individual gas flues which are located adjacent one another, will be facilitated.

The invention further aims to provide a structure wherein the lower distributors of the mentioned groups of tubes extend from a main distributor located in the longi-

2

tudinal direction of the steam generator on the side of the gas flues opposite the combustion space whereas the upper collectors of the individual groups are located transverse to the gas flow and are connected to a main collector which is arranged above the wall between the combustion chamber and the adjacent gas flues.

According to still another object of the invention, the tubular groups of the convection heating surface may be so constructed that they extend through several of the gas flues which are located one at the side of another one wherein a partition vertical to the tubular groups separates the gas flues from one another. However, it is also possible for each single gas flue to have its own complete tubular groups.

Further objects and details of the invention will be apparent from the description given hereinafter and the accompanying drawing illustrating an embodiment thereof by way of example.

In the drawing:

FIG. 1 is a vertical cross-section of a steam generator according to the invention along line 1—1 of FIG. 2.

FIG. 2 is a horizontal cross-section of the boiler in a plane through the center of the burner opening, visible in FIG. 1.

FIGS. 3 and 4 are cross-sections according to the lines 3—3 and 4—4 respectively, of FIG. 2.

FIGS. 5 and 6 are side elevation and rear view of a bank of a tubular group being part of the illustrated steam generator.

FIGS. 7 and 8 are side elevation and rear view of a modified bank of tubes.

FIGS. 9 and 10 are side elevation and rear view of a bank of still another form of tubular elements.

FIG. 11 is a cross-section along line 11—11 of FIG. 2.

FIG. 12 is a side elevation and

FIG. 13 is a top plan view of a portion of two modified tubular banks with a common connecting piece.

FIG. 14 illustrates the manner in which the economizer tubes 16 are supported.

FIG. 15 is a cross-section along line 15—15 of FIG. 14, and

FIG. 16 is a modified portion of a steam generator with differently arranged return pipes.

Referring now to the drawing, a steam generator according to the invention is provided with an opening 1 for an oil burner (not shown) in its front wall 1'. As indicated by the arrow a in FIG. 2, the flame is conducted in a horizontal direction through the combustion chamber 2. The front wall 1', outer side wall 5' and rear wall 6' are lined with radiantly heated tubes 3, 5 and 6, respectively, whereas the inner side wall of the combustion chamber is formed by a series of tubes closely adjacent one another or the wall may be made of refractory material and lined by such tubes. The bottom 7 is not cooled in the illustrated example. In a boiler of this kind, a grate (not shown) may be arranged at the bottom so that the boiler can be heated with coal.

The inner side wall of the combustion chamber with the tubes 4 forms a gas-tight wall which separates the combustion chamber from the first gas flue 8. At the rear end of the combustion space, the tubes 4 are arranged at a larger distance from each other or they are staggered so that the gases from the combustion chamber can enter the gas flue 8 from the rear end thereof.

In the illustrated example there are located in the gas flue 8, first, a steam generating heating surface 10, then, a super-heating surface 11 and adjacent thereto, again a steam generating heating surface 12. At the front end of the flue 8, the gases are conducted into the second gas flue 13, separated from the first one by a partition 44, which, at its front end, leaves an opening 45 for the passage of the gases. In flue 13 two steam gen-

erating heating surfaces 14 and 15 and an economizer 16 are located. The gases leave the boiler at 17. In FIG. 1, the steam generating heating surfaces 10 in the first gas flue 8 and the economizer heating surface 16 in the second gas flue 13 and also the gas exit are visible.

FIG. 3 shows the super-heater heating surface 11 in the first gas flue 8 and the steam generating heating surface 15 in the second gas flue 13.

In FIG. 14 both the steam generating heating surfaces 12 and 14 are visible. All these steam generating heating surfaces, located in the gas flues, are formed of parallel banks of the same kind of tubes.

A tubular bank is illustrated in FIGS. 5 and 6. It consists of a lower distributor 18 and an upper collector 19 between which the heated tubes 20 and 20' are arranged. The distributors 18 of the banks extend from a longitudinal main bank distributor 21. The bank collectors 19 open into the longitudinal main bank collector 22. If, as in the illustrated embodiment, a steam generating heating surface is arranged in the first flue 8 and an economizer heating surface 16 in the second flue 13, sideways of the steam generating heating surface, an extension or connecting piece 23, as shown in FIG. 1, will be connected to each lower bank distributor 18 of a tubular bank of FIGS. 5 and 6 in order to connect the distributor 18 with the main distributor 21. If a super-heater 11 is arranged in the first flue and a steam generating heating surface 15 in the second flue, as shown in FIGS. 2 and 3, a connecting or extension piece 24 will be connected to each upper bank collector in order to connect these collectors with the longitudinal main bank collector 22. The extension pieces 24 may simultaneously serve as supports from which the tubes of the super-heating surface may be suspended, as clearly visible in FIGS. 11, 12 and 13. Similarly, the tubes of the economizer 16 may be supported and bear on the intermediate pieces 23, as shown in FIGS. 14 and 15.

If steam generating heating surfaces are arranged side by side in the first and second flues, as shown in FIG. 4, two sets of tubes 20 and 20' may be connected according to FIGS. 5 and 6, that means, the tubes of the one set may be bent at their lower ends and the tubes of the other set at their upper ends. However, in all instances, the tubular elements used are equal and it is possible to produce such tubular elements according to one drawing, with the same tooling, whereby the costs will be substantially reduced. By changing the number of the groups of banks in the gas current in front and in the rear of the super-heater, it is possible to adapt the same structural element to the prevailing conditions of pressure or super-heated steam temperature. It is also possible to operate with the same type of tubular elements within certain output limits. With larger output changes, tubular elements with other dimensions as to height or width may be selected.

As it will be clear from FIGS. 1, 3 and 4, covers 25 are provided to close the space on top of the gas flues 8 and 13. Owing thereto, the convection heating surfaces in the gas flues are readily accessible from the top so that, after the removal of the cover, the heating surfaces in the gas flues can be cleaned, if necessary by hand, or repairs of the tubular groups can be performed and the super-heater and economizer heating surfaces can be removed through the top.

If the tubular elements are made according to FIGS. 5 and 6, cleaning is facilitated inasmuch as the distributor 19 is located somewhat laterally on account whereof the individual tubes are better accessible from the top. The production of the tubular elements is done in such a manner that the tubes are bent inwards on the one end and the straight ends of the tube 20 are inserted into the distributor 18 whereas the straight ends of the tube 20' are inserted into the collector 19.

Modified forms of the banks are illustrated in FIGS. 7 to 10. In the form of FIGS. 7 and 8, the distributors

18' and collectors 19' are connected to each other only by straight tubes 26 centrally inserted into the distributor 18 and collector 19. This form of production is relatively simple. However, less heating surface can be provided within a given space if it is required that the collectors 19 are somewhat distanced from each other in order to allow for cleaning or accessibility. In the form according to FIGS. 9 and 10, only straight tubes 27 are also used which, however, are eccentrically secured to the distributor 18" and collector 19". From the longitudinal section of FIG. 11 through the first flue 8, it is apparent how the super-heater tubes are suspended from the intermediate pieces 24 which connect the collectors of the tubular elements of the second flue to the longitudinal main bank collector 22, visible in FIGS. 1, 3 and 4. If the bank collectors 19 are located relatively closely to each other, the intermediate connecting pieces 24 would have to be located also close to each other and it would be impossible to pass the super-heater tubes between two bank collector tubes. For this reason, it is proposed to connect the distributors 19 of two or several tubular elements in the second flue to one connecting intermediate piece 24' as this is illustrated in FIGS. 12 and 13.

FIGS. 14 and 15 show how the economizer tubes 16 are supported on the extension pieces 23 which connect the distributors 18 to the main longitudinal distributors 21.

In order to render the cleaning of the spaces below the heating surfaces of the first gas flue 8 possible, a funnel-like structure 28 according to FIG. 11 may be provided under these heating surfaces. In the second flue 13, funnels are also arranged (shown in dash lines) which are staggered with respect to the funnels in the gas flue 8, so that cleaning openings 29 may be passed through the funnel saddles 46 of the gas flue 13 without permitting the gases to pass directly from one flue to the other except through the aforementioned opening 45.

The water circulation occurs in the boiler according to the invention in the following manner:

From the drum 31 boiler water flows through the down-comers 32 to the longitudinal distributor 33 on the outer side wall 5' of the combustion chamber and from there to the transverse distributors 34 and 34' at the front wall and rear wall, respectively, of the combustion chamber. The transverse distributors are connected by the longitudinal distributor 35 at the inner side 4 of the combustion chamber. The transverse distributors 34 and 34' are extended and connected to the longitudinal distributor 21 of the convection heating surface and supply the latter with circulation water. The side wall tubes 4 and 5 of the combustion chamber open into a longitudinal collector 36 which is connected to the drum 31 through front and rear wall collectors 37. In addition, a steam conduit 38 connects the longitudinal collector 36 with the drum 31. The collector 22 to which all the tubular elements of the steam generating heating surfaces of the flues 8 and 13 are connected is also in communication with the drum 31 through the collectors 37 and steam conduits 39. It is advisable to locate the collector 22 above the inner side wall 4 of the combustion chamber because in that event the tubes of the heating surface in the gas flue can be placed close to this side wall.

In order to increase the water circulation in the tubular elements of the convection heating surface, collector 22 may be connected by tubes 40 with the vertical return tubes 41 so that a separate circulation occurs from the collector 22 back to the distributor 21 and that accordingly the drum can be arranged relatively far from this heating surface so that one need not be afraid of a too weak circulation in the convection heating surface.

Suitably the drum bears on the down pipes 32 and the distributors 33, 34, 35 and 21 together with the return pipes 41 and the upper collectors 36, 37 and 22 will be combined into a boiler framework whereby the entire

boiler can be constructed so as to require relatively very little space.

With a particularly long boiler of this type, it may be advisable to connect the upper ends of the vertical return tubes 41, as in FIG. 16, by a longitudinal tube 42 and to arrange additional return tubes 43 distributed over the entire length of the tube 42 and connecting these tubes with the distributor 21.

In the embodiment according to FIGS. 1 to 4, the partition 44 between the gas flue 8 and the flue 13 is illustrated as made of stone or other refractory material. This partition can be installed from the spaces between the individual heating surface groups 10, 11, 12, 13, 14, 15, 16. However, it is also possible and advisable, in the higher temperature range, to form this partition between the first and second flues of steam generating tubes.

This can be done in such a way that one arranges in lieu of the partition of refractory material, fin-provided tubes on the bank distributor tubes 18 whereby a gas-tight closure from one gas flue to the other will be formed. Special tubes can be arranged in the spaces between the individual groups of heating surfaces.

It will be apparent to those skilled in the art that many alterations and modifications of the structure illustrated and described can be made without departure from the essence and spirit of the invention which for that reason shall not be limited but by the scope of the appended claims.

I claim:

1. A steam generator comprising a combustion chamber and at least one gas flue on substantially the same bottom level as and laterally of said combustion chamber on the one side thereof and extending substantially the height and the length of said combustion chamber, said steam generator having a front wall with an opening therein for fuel supply to the combustion chamber, a rear wall, an outer side wall opposite said flue, an inner side wall between said combustion chamber and said flue, and an outer flue wall opposite said inner side wall, openings being provided in the rear end of the inner side wall and the opposite end of the outer flue wall so as to cause a substantially horizontal current of the combustion gases in the flue parallel to a lengthwise flow of the combustion gases in the combustion chamber; groups of parallel banks of parallel convection heating tubes in said flue, said banks extending substantially through the entire height of the flue and including individual bank distributors and collectors extending transversely of the direction of the gas current in said flue, a steam separator drum lengthwise and on top of the outer side wall of said combustion chamber, and a removable top cover of said steam generator above said flue, a free space being provided on top of said groups of banks between said bank collectors and said cover.

2. A steam generator comprising a combustion chamber and at least two gas flues on substantially the same bottom level as and laterally of said combustion chamber on the one side thereof and extending substantially the height and the length of said combustion chamber; said steam generator having a front wall with an opening for fuel supply to the combustion chamber, a rear wall, an outer side wall opposite said flues, an inner side wall between said combustion chamber and the first one of said gas flues, a partition between said gas flues and an outer flue wall of said second flue opposite said partition, openings being provided in the rear end portions of said inner wall and said outer flue wall and in the front end portion of said partition so as to cause a substantially horizontal current of the combustion gases in the flues parallel to a lengthwise current of the gases in the combustion chamber; groups of parallel banks of parallel convection heating tubes in said flues, said banks extending substantially through the entire height of the flues and including individual bank distributors and bank collectors

collectors extending transversely of the direction of the gas current in said flues; a steam separator drum lengthwise and on top of the outer side wall of said combustion chamber, and a removable top cover of said steam generator above each of said flues, free spaces being provided on top of said groups of banks between said bank collectors and said cover.

3. A steam generator comprising a combustion chamber and at least two gas flues on substantially the same bottom level as and laterally of said combustion chamber on the one side thereof and extending substantially the height and the length of said combustion chamber; said steam generator having a front wall with an opening for fuel supply to the combustion chamber, a rear wall, an outer side wall opposite said flues, an inner side wall between said combustion chamber and the first one of said gas flues, a partition between said gas flues and an outer flue wall of said second flue opposite said partition, openings being provided in the rear end portions of said inner wall and said outer flue wall and in the front end portion of said partition so as to cause a substantially horizontal current of the combustion gases in the flues parallel to a lengthwise current of the gases in the combustion chamber; groups of parallel banks of parallel convection heating tubes in said flues, said banks extending substantially through the entire height of the flues and including individual bank distributors and bank collectors extending transversely of the direction of the gas current in said flues; a steam separator drum lengthwise and on top of the outer side wall of said combustion chamber, one main bank distributor located at the foot of said outer flue wall and connected to said individual bank distributors in both flues, additional distributors along the foot ends of the walls of said combustion chamber and connected to said main bank distributor, and downcomers at the ends of said drum connecting the latter to said additional distributors.

4. A steam generator as in claim 3, further comprising a main bank collector located above said inner side wall and connected to said individual bank collectors, risers lining the combustion chamber on both side walls and being inwardly bent with their upper portions, a common longitudinal collector to which said risers are connected, and connector tubes connecting said main collector and said common collector to said drum.

5. A steam generator as in claim 4 wherein said main bank collector is located within a free space above the inwardly bent portions of said inner wall risers.

6. A steam generator comprising a combustion chamber and at least two gas flues on substantially the same bottom level as and laterally of said combustion chamber on the one side thereof and extending substantially the height and the length of said combustion chamber; said steam generator having a front wall with an opening for fuel supply to the combustion chamber, a rear wall, an outer side wall opposite said flues, an inner side wall between said combustion chamber and the first one of said gas flues, a partition between said gas flues and an outer flue wall of said second flue opposite said partition, openings being provided in the rear end portions of said inner wall and said outer flue wall and in the front end portion of said partition so as to cause a substantially horizontal current of the combustion gases in the flues parallel to a lengthwise current of the gases in the combustion chamber; groups of parallel banks of parallel steam generating tubes, said groups being located in said flues, respectively, said banks extending substantially through the entire height of the flues and including individual bank distributors and bank collectors extending transversely of the direction of the gas current of said flues, a main bank distributor to which said individual bank distributors of both flues are connected, and a main bank collector to which said individual bank collectors of both flues are connected, said main bank distributor being located at the foot of said outer flue

wall, and said main bank collector being located on top of said inner wall, said individual bank distributors of said first flue including tubular connecting pieces extending through said partition and connecting said individual bank distributors to said main bank distributor, and said individual bank collectors of said second flue including tubular connecting pieces extending through said first flue and connecting said individual bank collectors to said main collector.

7. A steam generator as in claim 6 wherein each two bank collectors of said second flue have one of said connecting pieces in common.

8. A steam generator as in claim 6, further comprising other heating surfaces such as a superheater and an economizer, such other heating surfaces being carried by 15 at least some of said connecting pieces.

9. A steam generator as in claim 2 wherein said distributor and collector of each bank of at least one of said groups are formed as headers located in vertical planes, respectively, slightly spaced from each other, the tubes of said each bank being bent, alternatingly at the 20 lower and upper ends, in the vertical plane parallel to the direction of the gas current, the bent lower ends being connected to one of said headers, and the bent upper ends being connected to the other header.

10

5

10. A steam generator as in claim 2 wherein the bottoms of said flues underneath said groups of banks are provided with a plurality of funnel-like dust collecting dips extending transverse with respect to the flues, the dips of the one flue being staggered with respect to the dips of the other flue, cleaning passages being provided in said outer flue wall in communication with said dips, respectively, said passages of said first flue extending through the risers of said dips between each two adjacent dips of said second flue.

11. A steam generator as in claim 3, said partition being formed of steam generating tubes.
